UNITED STATES PATENT OFFICE.

WILLIAM THOMAS WATSON, OF VICTORIA, CANADA.

LIFE-GUARD FOR TRAM-CARS.

SPECIFICATION forming part of Letters Patent No. 668,313, dated December 4, 1900.

Application filed August 21, 1900. Serial No. 27,622. (No model.)

To all whom it may concern:

Be it known that I, WILLIAM THOMAS WATSON, a subject of the Queen of Great Britain, and a resident of Victoria, in the Province 5 of British Columbia, Dominion of Canada, have invented a new and Improved Life-Guard for Tram-Cars, of which the following is a full, clear, and exact description.

My invention relates to life-guards or fenders for street-cars, such as electric cars or cable-cars, and has for its object to provide a reliable and comparatively simple car-fender easily adjustable to different cars and having an improved locking device.

15 The invention will be fully described hereinafter with reference to the accompanying drawings, which illustrate, by way of an example, a car-fender constructed according to my invention. The features by which my invention is distinguished from prior constructions will then be particularly pointed out in the appended claims.

In the drawings, Figure 1 is a perspective view showing one end of a car provided with 25 my improved fender or life-guard. Fig. 2 is an inverted plan thereof. Fig. 3 is a sectional elevation on line 3 3 of Fig. 2. Fig. 4 is a detail plan drawn upon an enlarged scale and showing the manner of securing the rubber 30 tube at the front of the fender. Fig. 5 is a detail plan of the foot-lever adapted to be operated by the motorman or gripman and the adjacent parts. Fig. 6 is a perspective view of a rack-bar connected with said foot-lever. Fig. 7 is a longitudinal section through 35 a side member of the fender-frame, and Fig. 8 is a detail side elevation of the attaching device of the fender.

Similar characters of reference indicate 40 responding parts in all the views.

Under the bottom A of the car are secured in longitudinal alinement with each other two sets of brackets or eyes B, in which are adapted to slide the longitudinal bars C. 45 Each of these bars has a pivotal connection with one end of a rod D, the other end of which is pivotally connected with a crank-arm E' on a shaft E, journaled in longitudinal ribs A' on the bottom of the car. The 50 shaft is under the influence of a spring F, so as to normally draw the bars C rearward. At or near its center the shaft has a forwardly-extending crank-arm E², from which a rack-bar G passes upward through the platform. The teeth of the rack-bar are adapted to be 55 engaged by a holding-pawl H, pivoted to the platform and pressed by a spring H' into engagement with said teeth, so as to lock the rack-bar G. At one side the rack-bar has a pivoted hook G', adapted to be engaged by a 60 foot-lever I, pivoted at I', the movement of the hook being limited by a pin G³. The upper end G² of the rack-bar is bent forward. The spring F, in connection with the springs c, mentioned hereinafter, turns the shaft E 65 after the operator has with his foot depressed the pawl H, so as to throw it out of engagement with the rack-bar G. The rack-bar is pressed rearward, so as to normally keep it in engagement with the pawl H by means of a 70 spring J, resting with its ends against the dashboard K.

At the sides of the bottom A are secured downwardly-projecting brackets of approximately triangular form, the members L L' of 75 said brackets meeting at their lower ends and one of them being extended to form a hook or seat L². On the other member L' is pivoted a catch M, adapted to close the opening formed by the hook L² and capable of being 80 held against pivotal movement by means of a collar or thimble N, mounted to slide on the said member. (See Fig. 8.)

The fender proper (which is detachable from the parts so far described) comprises a 85 transverse shaft O, which is supported by the hooks L² and carries arms P, located in the path of the bars C. The shaft also has downwardly-extending arms Q, the lower ends of which are approximately horizontal and are 90 provided with a series of apertures, such as Q'. The two ends of these arms Q are rigidly connected with brackets R' on the tubular rear sections R of the side members of the fender-frame, so that said side members 95 swing in unison with the shaft O. Cross-bars S connect said tubular sections. The front sections T of the side members slide within the tubular sections and are pressed forward by coiled springs U, located within 100 the sections R and abutting at their rear ends against screws U'. The front ends of the

- sections T are connected by a cross member T', the members T T' forming together a U-shaped sliding section. An angular or L-shaped member T² is located at each corner 5 of said sliding section, and said members T² are grooved to seat a rubber tube V, held in position by means of a threaded rod or wire W, passed therethrough and fastened to brackets T³ by means of nuts W'.
- 10 To the cross member T' is secured the front bed X of the fender. This bed is curved upwardly at its rear end, so as to form a pocket, and may consist of a network of wire or other sufficiently strong and yielding material, or, 15 as shown, of longitudinal steel strips or slats. At their upper or rear ends these slats are formed with eyes X', through which passes a hinge-rod Y, held in position by nuts Y'. This rod also passes through eyes Z' at the 20 lower end of the rear bed Z, which extends in front of the dashboard K and stands upright. This bed also may consist of wires or of longitudinal slats, their rear ends being bent, as at Z², and being connected with a transverse 25 stiffening-bar Z³, which may be straight, as shown, but is preferably curved to conform to the shape of the dashboard K. Instead of employing nuts Y', I may provide eyebolts as an equivalent.
- 30 The rear sections R of the fender-frame have brackets R² in advance of the brackets R', and to these brackets are attached chains a, extending to the hinge-rod Y and limiting the upward movement of said rod. From the 35 arms Q pivoted bars b extend upward and connect with the front ends of springs c, the other ends of which are fastened to hooks d on the dashboard. (See Fig. 1.) Flexible connections, such as chains c', extend 40 forwardly from the upper ends of the arms b to the bar Z³ of the upper bed Z. To hold the fender in the inactive position shown in dotted lines in Fig. 3, I may employ a chain e, engaging the rubber buffer V, and a hook f 45 on the dashboard K. A bracket g may be secured to the dashboard to guide the fender.
- The two beds X and Z of the fender are yielding, as described, and the force of a 50 shock is further broken by the rubber buffer V and by the fact that the front bed can slide rearward against the tension of the springs U. The fender is normally held at a sufficient distance above the track to clear minor objects. In case of an emergency the 55 gripman or motorman depresses the lever I, which lifts the rack-bar G, the pawl H engaging the teeth as they ascend through the platform and preventing the fender from rising. The bars C press outward on the arms 60 P, causing the fender to drop at the front end T'. When the fender is to be raised back to its initial position, the operator presses the pawl H to release the rack-bar G, and the action is then as explained above.
- 65 The fender can therefore be left at any de-

sired height from the rails, and locked against rising, but would not be prevented from dropping of its own accord if any obstacle fell on it.

It will be observed that by simply detaching the springs c from the hooks d and the shaft O from the hooks L² (see Fig. 8) the fender proper can be readily removed from the car. Also after removal of one of the nuts Y' the hinge-rod Y may be withdrawn, 70 thus severing the connection between the beds X and Z and facilitating repairs. Further, the length of the chain a may be altered according to the height of the car-bottom A above the ground. In bringing the 75 fender into the position shown in dotted lines in Fig. 3 the shaft O forms the fulcrum or center of motion, and, moreover, the two beds X and Z fold on the hinge-rod Y.

Having thus described my invention, I 80 claim as new and desire to secure by Letters Patent—

1. A car-fender comprising a fender-frame made of a relatively stationary rear section and a front section mounted to slide forward 90 and backward in relation to the rear section, a normally-inclined rear bed the upper end of which is adapted for attachment to the car, while its lower end is at a distance above the rear frame-section, a front bed the rear 95 end of which is hinged to the lower end of the rear bed, while its front end is attached to the sliding front section, thus leaving a clear space below the upper bed immediately in the rear of the rear portion of the front bed, and flexible connections extending from the rear frame-section to the hinge connecting the two beds, at the ends of said hinge so as not to encroach upon the said clear space.

2. The combination of the fender having a 100 frame pivoted to the car, and provided with extensions or arms, rods mounted to slide longitudinally on the car and arranged to engage said arms, a spring-pressed rock-shaft 105 operatively connected with said rods, a rack-bar connected with the shaft and extending through the platform of the car, a holding-pawl engaging said rack-bar, and a foot-lever having lifting engagement with said rack-bar.

3. A car-fender having a U-shaped front member with angular or L-shaped members at the corners thereof, and outwardly-projecting brackets adjacent to said L-shaped members, a tubular rubber cushion seated in 110 said L-shaped members, a threaded rod or wire passing through the cushion and through the brackets, and nuts screwing on the ends of said rod.

4. A car-fender, having a fender-frame 115 comprising a relatively stationary rear section and a spring-pressed, longitudinally-slidable front section, a front bed the front end of which is connected with the front section of the fender-frame, a rear bed the front 120

end of which has a hinge connection with the rear end of the front bed, arms pivoted to the rear frame-section, springs extending rearwardly from the upper ends of said arms, 5 to connect them with the car-frame, and flexible connections extending forwardly from said arms to the upper end of the rear bed.

In testimony whereof I have signed my name to this specification in the presence of two subscribing witnesses.

WILLIAM THOMAS WATSON.
